UNITED STATES PATENT OFFICE.

SAMUEL DRESNER, OF CHICAGO, ILLINOIS.

CORNER-PIECE OR EDGE-PIECE PROTECTION FOR TRAVELING BAGS.

Application filed July 27, 1921. Serial No. 437,920.

To all whom it may concern:

Be it known that I, SAMUEL DRESNER, citizen of the United States, residing at Chicago, Illinois, have invented certain new and useful Improvements in a Corner-Piece or Edge-Piece Protection for Traveling Bags; and I do hereby declare the following to be a full, clear, and exact description of the invention, such as will enable others skilled in the art to which it appertains to make and use the same.

My invention relates to traveling bags, suit cases and the like, its general objects being those of improving the strength and durability of such an article and also of enhancing the appearance of the same.

In making hand bags of this general class, it has long been customary to increase the strength, durability and appearance of the same by providing its sides and ends adjacent to the bottom of the bag with raised portions which will receive a large share of the side thrusts and end thrusts to which such bags are ordinarily subjected. These raised portions are sometimes integral with the adjacent side or end portions of the bag, being outwardly embossed and held so by underlays of cardboard or the like. More often, this general result is accomplished by affixing reinforcing members in the form of corner-pieces to the lower quarters of the bag, and sometimes each protecting or reinforcing piece has been run continuously from one corner to the next so as to afford a more extended protecting edge-piece. In practice, such affixed corner-pieces or other edge-pieces are commonly made of leather and secured to the adjacent sides of the bag by stitches running through both the main leather covering of the bag and the edge-piece adjacent to an edge of the latter.

While this method of attaching the reinforcing pieces has proven quite practical, it is not entirely adequate in case the bag rubs against an adjacent object in such a way as to cause a downward strain to be exerted against the upper edge of the corner-piece or longer edge-piece. Under such a condition, the upper edge of the reinforcing piece is apt to be turned outward or away from the leather of the bag, thus interfering with the appearance of the bag and also presenting an effectively widened upper ledge adapted to catch more readily on some external object. Then if such a scuffing of this edge by contiguous objects is repeated, this may

easily cause a strain tending to pull the corner-piece or longer edge-piece away from the bag, thereby ripping the stitching and loosening the reinforcing piece.

60

Likewise, if the raised corner or edge portions are integral with the main leather parts of the bag covering, a similar rubbing comes entirely on the upper shoulders of the same, thereby causing undue wear on these.

65

My present invention aims to overcome these serious shortcomings providing the bag with means for guarding the upper and lateral edges of such auxiliary reinforcing members or the shoulders of the corresponding integral side and end portions by providing guard formations for receiving at least part of the rubbing action. Moreover, my invention desirably aims to arrange the needed guard means in such a manner that they will also add considerably to the appearance of the bag. Furthermore, my invention aims to accomplish these results with a simple and inexpensive construction and one that will require relatively little additional work in the manufacturing of the bag. It also aims to provide a protecting and ornamenting guard formation for the above purposes which can be applied with equal facility to hand bags of various shapes and types, it being understood that the term traveling bag is here used in a broad sense and not as denoting any particular shape or type of hand bag. Illustrative of my invention, Fig. 1 shows a traveling bag equipped with my invention as employed in connection with auxiliary reinforcing members of a common corner piece type.

70

Fig. 2 is a fragmentary perspective view showing the lower end portion of a bag having my invention employed thereon in connection with an auxiliary edge-piece which forms a single and continuous reinforcement for the two lower corners at one end of the bag and for the intervening lower edge at this same bag end.

75

Fig. 3 is an enlarged transverse section taken through the bag of Fig. 1 along the correspondingly numbered line of that figure.

80

Fig. 4 is a similar section drawn on a smaller scale and showing my invention as used in connection with an auxiliary reinforcing edge-member which is not raised or embossed.

85

Fig. 5 is a somewhat similar section show-

ing my invention as employed in connection with an edge-piece formed from the main leather covering of the bag.

In applying auxiliary corner-pieces to traveling bags, it has been customary to affix these to the outside of the bag, and it has also been customary to enhance the effective thickness of such a corner-piece by interposing a correspondingly shaped piece of card-board between the corner-piece and the adjacent leather covering of the bag, so that the corner-piece when applied will be outwardly raised or embossed. For example, Fig. 3 shows portions of a traveling bag in which the inner lining 1 is spaced from the outer leather covering 2 by the usual card-board or fiber stiffening 3, the leather side 2 being desirably continued under the bottom of the bag so as to overlap the corresponding leather bottom piece 4. The auxiliary leather corner-piece 5 as applied to the outer face of the bag is likewise lapped under the bottom of the bag, being here shown as spaced from the leather side of the bag by a cardboard insert 6 and as secured to the side of the bag by stitching 7 extending parallel and close to the upper edge 8 of the corner piece.

With the auxiliary corner piece thus disposed, it will be obvious that the upper edge 8 of the corner piece is continuously exposed to the possible engagement with extraneous objects, and such engagement if downwardly directed will tend to turn this edge and to 30 rip the seam 7. To guard against this, I emboss the leather side 2 of the bag in an outward direction immediately above and parallel to the said edge 8 so as to form an outwardly directed ridge 9 extending raised beyond the edge 8 of the reinforcing corner piece. Then I maintain this guard ridge 9 in its outwardly directed position by inserting a filler 10 of rope or the like between this embossed portion of the leather covering and 40 the cardboard lining 3 of the bag. I desirably also keep the filler 10 from sliding upwardly along the bag by an auxiliary row of stitching 11 extending through the leather covering 2 and the cardboard lining 3 of the bag adjacent to the upper edge of the ridge 9.

Thus arranged, it will be obvious from Fig. 3 that any object sliding down along the side of the bag from above the ridge 9 will be deflected outwardly of the bag by this 55 ridge and will ride over the upper end of the corner piece without engaging the exposed edge 8 of the latter. In other words, the embossed ridge 9 forms a guard which will effectively prevent the engagement of extraneous objects with this upper edge of the corner-piece, thereby guarding both against the insightly turning of this upper edge and against a ripping of the stitches which hold the corner-piece in position.

Moreover, by keeping this embossed guard

rigidly parallel to the edges of the corner-piece I provide an ornamentation which considerably enhances the appearance of the bag, so that I accomplish two highly important purposes with a simple and easily manufactured construction. Furthermore, the same arrangement can readily be applied regardless of the shape or size of the reinforcing edge members of which the corner pieces are the most commonly used types. 70 For example, Fig. 2 shows a bag in which the edge member 12 runs continuously along the end of the bag and includes the equivalent of two separate corner pieces. So also, while I have heretofore described my invention as used in connection with a corner-piece maintained in outwardly embossed relation by an underlay 6 of cardboard, I do not wish to be limited to this or other details of the construction and arrangement thus disclosed. Obviously, the arrangement may be modified in many ways without departing from the spirit of my invention or from the appended claims, and the guard formation may be varied both in width and in height. 80 For example, Fig. 4 shows a bag portion in which my invention is employed in connection with the reinforcing edge-piece which is not outwardly embossed but which contacts flatwise with outer face of the bag, and also 85 shows the use of a more flat form of inlay 13 under the guard ridge formation which will afford a somewhat different ornamental appearance.

So also, my invention may be employed to 100 good advantage in increasing both the durability and the appearance of a bag having its main leather covering outwardly embossed to afford a raised portion adjacent to the lower edge of the bag, as shown in Fig. 5, 105 by providing a similar guard or ridge which will share the rubbing with the shoulder 14 of the embossed portion and hence will greatly increase the wear.

I claim as my invention:—

1. A traveling bag embodying a reinforcing member disposed on the outside of the bag, the main portion of the bag adjacent to the upper and lateral edges of the reinforcing member being raised beyond the said edges to guard the latter against scuffing.

2. A traveling bag embodying a reinforcing member disposed on the outside of the bag and stitched to the bag by a seam adjacent to an edge of the reinforcing member, 120 the main surface portion of the bag adjacent to and above the said edge being raised to afford a guard extending substantially parallel to the said edge.

3. A traveling bag embodying a reinforcing member disposed on the outside of the bag and stitched to the bag by a seam adjacent to the upper and lateral edges of the reinforcing member, the main surface portion of the bag adjacent to the said edges 130

being raised to afford a guard extending substantially parallel to the said edges for the entire length thereof, and a filler under the said raised guard for maintaining the latter in its raised position.

4. The combination with a traveling bag having an externally projecting reinforcing corner piece secured thereto, of a guard formation upon the surface of the bag adjacent to an edge of the corner piece and projecting outwardly of the bag considerably beyond the said edge, the said guard formation being integral with the outer covering of the bag, and a filler behind the guard formation for maintaining the latter raised.

5. In a leather covered traveling bag, a corner piece affixed to the exterior thereof at a lower corner of the bag and secured to the bag by stitches including stitching extending adjacent to the upper edges of the corner piece, the portion of the leather bag covering to which the corner piece is affixed having an outwardly directed ridge embossed therefrom substantially parallel and close to the said edge and projecting outwardly of the bag beyond the said edge to guard the said edge against contact with external objects.

6. In a leather covered traveling bag, an edge reinforcement extending along the

lower edge of the bag and secured to the exterior of the leather bag covering by stitching disposed adjacent to the upper edge of the said reinforcement, the portion of the leather bag covering to which the reinforcement is affixed having an outwardly directed ridge embossed therefrom and extending substantially parallel and close to the said upper edge of the reinforcement and extending outwardly of the bag at least as far as the said reinforcement.

7. In a leather covered traveling bag, a corner piece affixed to the exterior thereof at a lower corner of the bag and secured to the bag by stitches including stitching extending adjacent to the upper and lateral edges of the corner piece, the leather bag covering having an outwardly directed ridge embossed therefrom substantially parallel and close to the said edge and projecting outwardly of the bag beyond the said edges to guard the said edges against contact with external objects and a filler within the said ridge, there being stitches through the bag adjacent to the said ridge for preventing a movement of the filler away from the corner piece.

Signed at Chicago, Illinois, July 25th, 1921.

SAMUEL DRESNER.
